UNITED STATES PATENT OFFICE.

HARRY B. PAGE, OF EAST HAVEN, CONNECTICUT, ASSIGNOR TO SARGENT & COMPANY, OF NEW HAVEN, CONNECTICUT.

PADLOCK FOR TIRE CARRIERS AND THE LIKE.

Application filed February 11, 1924. Serial No. 692,005.

My invention relates to padlocks and more particularly to a padlock provided with an improved type of shackle mechanism, which co-operates with the locking mechanism within the lock case and with the parts which are adapted to be secured by the lock.

In some situations it is difficult to employ a padlock provided with the ordinary shackle which is usually U-shaped in form, the end 10 of one of the legs of the U being permanently but movably secured within the lock, and the other end co-operating with the locking mechanism to secure the shackle in closed or locked position. In some cases when a 15 shackle of this character is made sufficiently large so that it may be secured in position with ease it will be quite loose when in locked position and an objectionable noise or rattle will result. This has been found to be true 20 especially in the use of padlocks in connection with tire carriers upon automobiles, and while the form of my invention shown in the drawings is particularly adapted to such use, it will be understood that the invention is 25 capable of broader application and the principles thereof may be used in other relations.

Further, in the type of padlock which I have illustrated as embodying my invention, the shackle member which is locked to the 30 case is arranged so that it may be rotated relatively to the case when in locked position so that the lock may not be destroyed by turning the shackle relatively to the case with a wrench or the like, as is sometimes the case 35 with padlocks in common use.

One object of my invention is the provision of a padlock provided with a novel form of shackle mechanism which may be inserted into the parts to be locked together with facility, and at the same time will efficiently lock 40 these parts together in the desired position.

Another object of my invention is to provide a padlock with a shackle member which may be detachably and adjustably secured to the lock and to provide the lock case with means permanently secured thereto to co-operate with the detachable shackle member to properly secure the locked parts together.

A still further object of my invention is the 50 provision of a padlock having a pair of separate but co-operating shackle members, one of which is permanently secured to the lock case and the other of which is detachably secured thereto, so that the lock case may

be applied to the members to be locked together from one side thereof and the detachable shackle applied from the other side.

Further objects of my invention are the provision of a padlock which may be simple in character and economically made but which will at the same time be effective in use and which may be easily secured in place, regardless of the position in which it is to be used.

To these and other ends, the invention consists in the novel features and combination of parts to be hereinafter described and claimed.

In the accompanying drawings:

Fig. 1 is a rear elevational view of a tire 70 carrier provided with a lock embodying my improvements;

Fig. 2 is a view partly in section of the lock and associated brackets;

Fig. 3 is a sectional view on line 3—3 of 75 Fig. 2;

Fig. 4 is a view similar to Fig. 1, showing a different form of tire carrier with which my lock may be employed;

Fig. 5 is a fragmentary view of the part 80 shown in Fig. 2, showing the manner of application of the lock, and,

Fig. 6 is a sectional view on line 6—6 of Fig. 4.

It will be understood that manufacturers 85 of automobiles use several different types of mechanisms to carry the spare tires, usually upon the rear of their automobiles. It will also be understood that my improved padlock may be used upon practically all of such 90 tire carriers now in use, and that the particular forms shown are merely illustrative of the various uses to which the lock may be put and are not to be considered as showing all of the uses contemplated.

In Fig. 1 of the drawings I have shown at 10 a tire carrier or rack which may be secured in any proper way to the body of an automobile, upon which rack is mounted the usual tire rim 11, carrying the tire 12. The tire 100 rack 10 may be provided with a pair of lugs 13 and 14, which are designed to engage or overlap the tire rim 11 to hold it in place. At the lower side of the rack 10 is secured an L shaped bracket 15, having its horizontal portion secured to the tire rack and provided with an upwardly extending portion 16, having therein a bolt opening 17, a shackle open-

ing 18 and an open-ended recess 19 upon the upper edge.

A clamp or bracket member 20 is pivotally connected to the part 16 of the bracket 15, by means of the bolt 21 passing through the bolt opening 17 and through a registering opening 22 in the part 20. The bracket member 20 is also provided with a shackle opening 23 designed to register with the opening 18, 10 and with an open-ended notch 24 in its upper edge designed to register with the notch 19 in the member 16. A depending or projecting lug 25 is provided at the lower free end of the bracket member 20, which lug is designed to engage the tire rim when in the position shown in Fig. 2, and co-operate with the lugs 13 and 14 to secure the rim in place.

The bracket member 20 is designed to be rotated upon the bolt 21 until the lug 25 no longer engages the tire rim and the rim may then be removed from the carrier rack. To prevent unauthorized removal of the rim and tire, the bracket members 15 and 20 are usually locked together so that the member 20 25 may not be moved to the disengaging position referred to above.

For this purpose, I have provided a lock comprising a case 30 provided with a lock cylinder 31, in which operates a key barrel 32. 30 A cylinder is also provided with a spring pressed bolt 33 designed to be operated by an eccentric lug 34 on the key barrel. The specific lock mechanism just described may be of essentially the same character as that shown and described in my co-pending application, Serial No. 612,150, filed January 11, 1923.

The lock case is provided with a shackle opening 36 adapted to receive the stem 37 of a shackle, which as illustrated, is in the form of a bolt provided with a head 38. The stem of the shackle is provided with a plurality of annular shoulders 39 to be engaged by the bolt 33 to lock the shackle in position in the lock case. The end of the bolt 33 which engages the shackle is beveled as shown at 40, and the annular shoulders 39 upon the stem of the shackle member are beveled upon one side so that the shackle may be freely inserted into the opening 36 regardless of the position of the bolt which is cammed rearwardly by the engagement of the beveled faces upon the shackled stem and upon the bolt to permit the reception of the shackled stem in the opening. The stem 37 of the shackle member is designed to be passed through the openings 18 and 23 and may be applied thereto from the side opposite that upon which the lock case stands.

60 The lock case is provided with a second shackle member in the form of a post 42, which is permanently connected to the case. As shown, the shackle post may be formed integrally with the lock case and may consist of a substantially straight post which ex-

tends outwardly from the case in a position substantially parallel to that assumed by the shackle stem 37.

With the form of tire carrier shown in Fig. 2, the post 42 is designed to be positioned in the recesses 19 and 24. While these recesses are open at their ends and are formed upon the upper edge of the bracket members 16 and 20, it will, of course, be understood that the post 42 could be inserted just as easily through registering perforations similar to those receiving the shackle stem 37, which may be used instead of the open-ended recesses.

70 As shown in Fig. 5, the lock case is applied at one side of the two bracket members to be locked together, while the stem 37 of the shackle member is inserted through the registering openings from the other side and inserted into the opening 36, where its shouldered end is engaged by the lock bolt 33. The proper number of annular shoulders 85 are provided upon the shackle stem 37 so that the lock case may be positioned closely against the bracket member 20, regardless of 90 its thickness.

In Figs. 4 and 6 I have shown a somewhat modified form of tire carrier in which a pair of lugs 52 and 53 are pivoted to the ends of the tire rack 54 and co-operate with a lug 55 to hold the tire in place. To the lugs 52 and 53 are pivoted links 56 and 57 which are pivoted together at 58. The link 56 may be substantially channel shaped in cross-section and may receive between its sides the link 100 57, as shown in cross-section in Fig. 6. The parts of these links are provided with aligned openings 59, 60 and 61, which are designed to receive the stem 37 of the detachable shackle bolt. This stem is received and secured in the lock case in the same manner as described in connection with the other figures of the drawing. The post 42 provided upon the lock case may, in this instance, engage the upper side of the link 56 110 so as to hold the lock firmly in place and prevent objectionable noise.

115 While I have shown and described some preferred embodiments of my invention, it will be understood that it is not to be limited to all the details shown but is capable of modification and variation within the spirit of the invention and within the scope of the appended claims.

120 What I claim is:—

1. In a tire lock, a case, a pair of cooperating members, one of said members consisting of a straight headless post permanently secured to the case and the other of said members comprising a headed bolt completely detachable from the lock body but adapted to be locked thereto in spaced parallel relation with said first member and on the same side of the case.

125 2. In combination with a plurality of parts 130

to be locked together and having aligned openings, a lock case having a pair of members connected thereto, one of said members having a head on one end and being adapted to be inserted through the openings from one side of the parts, and the other member being secured to the lock case and adapted to be inserted through the openings from the other side thereof.

10 3. In combination with a pair of members adapted to be locked and having aligned openings, a lock comprising a case, a bolt adapted to be locked to the case and designed to pass through said openings, and means permanently secured to the case adapted to engage said members to prevent rotation of the case relative to the members.

In witness whereof, I have hereunto set my hand this 8 day of February, 1924.

HARRY B. PAGE.
